(57) **CLAIM**

The ornamental design for an orthodontic molar tube, as shown and described.

DESCRIPTION

FIG. 1 is a perspective view of an orthodontic molar tube showing our new design with the tube mounted on a bonding pad shown in phantom;

FIG. 2 is a front elevational view thereof;

FIG. 3 is a rear elevational view of the orthodontic molar tube of our new design with the tube mounted on a bonding pad shown in phantom;

FIG. 4 is a top plan view of the orthodontic molar tube of our new design;

FIG. 5 is a bottom plan view thereof;

FIG. 6 is an end elevational view thereof;

FIG. 7 is an end elevational view thereof from the opposite side;

FIG. 8 is a perspective view of the orthodontic molar tube showing our new design with the tube mounted on a band shown in phantom;

FIG. 9 is a perspective view of the orthodontic molar tube showing our new design with the tube mounted on a plastic pad shown in phantom;

FIG. 10 is a perspective view of a modified orthodontic molar tube showing our new design with the tube mounted on a bonding pad shown in phantom; and,

FIG. 11 is a front elevational view of the molar tube of FIG. 10.
